DESIGN FOR A COMBINATION COOLER AND FREEZER

Arthur H. Boileau and Charles J. Rayman, Cedar
Rapids, and Hershel W. Miller, Davenport,
Iowa, assignors to Cherry-Burrell Corporation,
Chicago, Ill., a corporation of Delaware

Application November 21, 1947, Serial No. 142,700

Term of patent 14 years

(Cl. D67—2)

To all whom it may concern:

Be it known that we, Arthur H. Boileau, Charles J. Rayman and Hershel W. Miller, citizens of the United States, residing respectively at Cedar Rapids, Cedar Rapids, and Davenport, in the counties respectively of Linn, Linn, and Scott and State of Iowa, have invented a new, original, and ornamental Design for A Combination Cooler and Freezer, of which the following is a specification, reference being had to the accompanying drawing, forming part thereof.

In the drawing

Fig. 1 is a left front perspective view of a combination cooler and freezer, showing our new design;

Fig. 2 is a right front perspective view thereof.

The rear side of the apparatus illustrated in the drawings is substantially plain.

The dominant feature of the design resides in the portion shown in full lines in the drawings.

We claim:

The ornamental design for a combination cooler and freezer, substantially as shown and described.

ARTHUR H. BOILEAU.
CHARLES J. RAYMAN.
